UNITED STATES PATENT OFFICE.

WILLY NOACK, OF GUBEN, GERMANY, ASSIGNOR TO CARL HEINZE A. G., OF GUBEN, PRUSSIA, GERMANY.

MACHINE FOR PREPARING MATERIAL FOR THE MANUFACTURE OF HAIR-FELT HATS.

Application filed June 5, 1924. Serial No. 718,116.

To all whom it may concern:

Be it known that I, WILLY NOACK, a citizen of the German Republic, residing at Guben, Prussia, Germany, have invented certain new and useful Improvements in Machines for Preparing Material for the Manufacture of Hair-Felt Hats, of which the following is a specification.

This invention relates to improvements in machines for blowing or cleaning fur, hair or the like adapted for use in the manufacture of felt hats.

This invention has for its principal objects to provide an improved means for uniformly feeding and evenly distributing loosened masses of hair into the initial blowing chamber of the machine, and at the same time freeing the admitted hair from relatively heavy admixtures of sand, pieces of hide, small shot, etc.; to provide a succession of blowing chambers beyond the initial blowing chamber, together with perforate hair advancing drums for each blowing chamber adapted to cooperate with the feeding and picking rollers of the successive blowing chambers; said perforate hair advancing drums being adapted to permit the passage of air currents transversely therethrough, and deflector means being provided beneath said hair advancing drums whereby the air passing through the latter is deflected to produce a counter air current toward the picking roller of each blowing chamber, so that the separation of foreign materials and undesirable coarse hair is more thoroughly and rapidly accomplished.

Another object of this invention is to provide a novel arrangement and construction of blowing chambers adapted to retain the dust, consequent upon the hair blowing operations, within the machine and confined against discharge into the air of the workroom wherein the machine may be located.

Other objects of this invention, not at this time more particularly enumerated, will be clearly understood from the following detailed description of the same.

In the accompanying drawings, Figure 1 shows a vertical longitudinal section of one embodiment of the novel fur or hair blowing and cleaning machine made according to the principles of this invention; Figure

2 is an end elevation of the same; and Figure 3 is a plan view of the same.

Similar characters of reference are employed in the above-described views, to indicate corresponding parts.

Referring to said drawings, the reference character 1 indicates the receiving bin or hopper at the receiving end of the machine, into which the hair or fur to be run through the machine is deposited. Access to the receiving bin or hopper may be had through a swinging door 2. Transversely disposed across the lower open end of said receiving bin or hopper 1 is a rotatable feed drum 3, which is provided upon its cylindrical surface with a plurality of outwardly projecting pins 4. Above the upper part of said feed drum 3 there is arranged a scraper plate 5 adapted to be spaced concentrically a suitable distance from the surface of said feed drum 3, and the front longitudinal edge of which is provided with a row of outwardly projecting take-off pins 6. Said scraper plate 5 is pivotally supported for transverse reciprocation above the surface of said feed drum 3 by means of supporting arms 7 which are fulcrumed on the axle of said feed drum 3. If desired, the supporting connections for said scraper plate 5 may be made adjustable so that the distance of said scraper plate 5 from the surface of the feed drum 3 may be variable, whereby the quantity of hair material taken up by said feed drum and conveyed into the machine may be regulated as desired. The reciprocation of said scraper plate 5 is attained by means of rotated crank wheels 12, the cranks 9 of which are adjustably fixed in radial slots 11 with which said crank wheels are provided, so that the stroke of said cranks 9 may be varied to in turn vary the limits of reciprocation of said scraper plate 5. Said scraper plate 5 is provided at its ends with pivots 8, intermediate which and said cranks 9 are arranged connecting rods 10 for translating the rotary movement of said crank wheels 12 into the desired reciprocatory movement of said scraper plate 5. Said crank wheels 12 are mounted on a transverse shaft 13, and one at least of said crank wheels 12 is provided with gear teeth at its periphery adapted to mesh with a gear 14 mounted

on a second transverse driven shaft 15, to thus transmit operative movement to said crank wheels 12.

Fixed on the shaft 15 so as to be rotated thereby is a rotary comb plate 16, the opposite free longitudinal edges of which are provided with a plurality of comb pins 17, which are adapted to cooperate or mesh with the pins 4 of said feed drum 3 beyond the receiving bin or hopper 1, so as to remove or take off the hair material from the feed drum as the same is carried into the machine.

Disposed beneath said comb plate 16 is a rotating transfer roller 18 to receive the hair material removed from the feed-drum 3 by said comb plate 16. Said transfer roller 18 delivers the hair material to and between a pair of feeding-in rollers 19 and 20. Cooperating with said feeding-in rollers 19 and 20 is a rotating picking roller 22 which teases out, loosens and separates the fibers of the hair material fed forward by feeding-in rollers 19 and 20. Cooperating with the roller 20 is a scraper plate 21 which prevents the winding up of the hair material thereon, so that the latter is properly presented to the action of the picking roller 22.

The said picking roller 22 is located at the lower end of an upwardly extending channel or well 25 which extends to and communicates with an initial blowing chamber 32. Arranged at the bottom of said channel or well 25 is a door 24 adapted to swing on a hinge connection 23. The door 24 opens to the atmosphere and thus permits air to enter the channel 25 below said picking roller 22. The rapid rotation of said picking roller 22 produces an upwardly rising current of air which passes through the channel or well 25 and into the initial blowing chamber 32. This upwardly rising air current carries the hair material upwardly into the initial blowing chamber 32, wherein the hair fibers are tossed, so that dust and dirt may drop by gravity out of the same. The tossed hair material descends at the forward side of the blowing chamber 32 upon a rotating perforate hair advancing drum 26. Said hair advancing drum 26 comprises a hollow cylindrical member, the walls of which may be made of coarse wire mesh, perforate sheet metal or the like so as to admit of air passing transversely through the drum, and so as to also permit dust and dirt to sift through the drum towards the closed under space of the machine which lies below the several blowing chambers.

Disposed adjacent to the forward side of said hair advancing drum 26 are a pair of feed rollers 27 and 28 which receive the hair material advanced by the drum 26. Cooperating with the upper feed roller 28 is a

scraper plate 29 to prevent the winding up of hair material on said feed roller 28. Cooperating with said feed rollers 27 and 28 is a rapidly rotated picking roller 30 which teases out, loosens and separates the hair fibers, and by reason of the upward air draft, which is produced by its rapid rotation, tosses the loosened hair fibers upwardly into the succeeding blowing chamber 32, adjacent to the bottom open end of which said picking roller 30 is located. Also disposed in the bottom open end of said succeeding blowing chamber 32, and forwardly spaced beyond said picking roller 30 and opposite thereto is a rotating perforate hair advancing drum 31. The moving air current produced by the rapid rotation of said picking roller 30 is caused to pass partially upward into the interior of said succeeding blowing chamber 32 and partially against and directly through the perforate hair advancing drum 31 into the said closed under space of the machine. Extending beneath said hair advancing drum 31, so as to swing on a pivotal connection 34, is a deflector plate 33, which deflects the air passing downwardly through said hair advancing drum 31, so that said air is not permitted to discharge straight down into the under space of the machine, but is directed more or less toward and in proximity to the picking roller 30 as a counter stream against the main stream of air which is produced by the rapid rotation of said picking roller 30. Said deflector plate 33 is adjustable toward and away from the underside of said hair advancing drum.

In hair blowing and cleaning machines it is generally the rule that a plurality of repetitions of the blowing processes are required to thoroughly loosen and clean the hair; consequently in the instant machine there are several successive blowing chambers 32 each equipped with feed rollers, picking roller, perforate hair advancing drum, and deflector plate beneath the latter, all arranged and related in the manner above described. In the drawings there are represented four blowing chambers succeeding the initial blowing chamber, but it will be understood that this number may be increased or decreased as may be advisable under varying conditions relating to the use of the machine.

The means for supporting and for adjusting the deflector plates 33 beneath their respective hair advancing drums, comprises a frame 35 to engage and support the undersides of said deflector plates 33. Said frame 35 is mounted on eccentrics 36, which are fixed on shafts 37. Said shafts 37 are rotatable from a point outside of the machine, whereby the successive deflector plates 33 may be respectively set more closely to the

perforate hair advancing drums of the successive blowing chambers, in the manner shown in Figure 1 of the drawings, or, if desired, may all be equally spaced from the 5 said hair advancing drums. The means for adjusting the said deflector plates is subject to more or less mechanical variation; consequently I do not limit myself to the specific means above described and as shown in the 10 accompanying drawings.

The machine is provided with power transmission means for driving the various rotatable elements thereof. As illustrated in the drawings said power transmission 15 means may comprise the following or any equivalent means:—

A drive shaft 39 is itself driven from any suitable source of power by pulleys 38. A driven shaft 42 is provided having a pulley 41 driven by a belt from a pulley 40 fixed on said drive shaft 39. The shaft 42 is provided with a graded or variable speed pulley 43 which drives, through a belt, another graded or variable speed pulley 44 which 20 is fixed on said shaft 15, to thereby rotate the latter and the comb plate 16 mounted thereon. The shaft 15 is provided with the heretofore mentioned gear 14 which meshes with the teeth of one of said crank wheels 25 12, to thus rotate said crank wheels and thereby actuate the connecting rods 10 to provide operative reciprocation of the scraper plate 5. The shaft 15 is also provided with a gear 45 which meshes with and 30 drives a gear 46 for rotating the lower feeding-in roll 19. Intermeshing spur gears or pinions 47 and 48 respectively mounted on the journals of said feeding-in rollers 19 and 20 serve to actuate the upper feeding-in 35 roller 20. In like manner the opposite journal of said feeding-in roller 19 is provided with a gear or pinion 49, which meshes with and drives a gear 50 mounted on the adjacent journal of said transfer roller 18. 40 Secured upon the opposite journal of said transfer roller 18 is a sprocket wheel 51 which drives a chain 52 which runs over a sprocket wheel 53 fixed on the shaft of said feed drum 3, thus actuating the latter.

Secured upon the drive shaft 39 is a drive pulley 54 which drives, through a belt, a pulley 55 which is fixed on the shaft of said picking roller 22, thus producing the operative rotation of the latter. The picking 55 rollers 30 are driven partly from the drive shaft 39 and partly from a lay shaft 55', said shafts having pulleys 56' for a transmission belt. On each shaft 39 and 55' is a pulley 56 which drives, through a belt, 60 the pulleys 57 respectively fixed on the journals of said respective picking rollers 30.

The means for driving the groups of feed rollers 27 and 28 and the several hair advancing drums 26 and 31, comprises a gear 65 and shaft transmission which receives its

motion from a driving bevel gear 58 mounted on an end of the shaft 42. Journaled in a bearing bracket 60 is a vertical spindle provided at its lower end with a bevel gear 59 which meshes with and is driven by 70 said bevel gear 58, and at its upper end with a bevel gear 61. Supported in suitable bearing brackets, so as to extend longitudinally along a side of the machine, is a shaft 63 upon which is fixed a bevel gear 75 62, which meshes with and is driven by said bevel gear 61. The lower feed rollers 27 are driven by intermeshing bevel gears 64 and 65 respectively mounted on said shaft 63 and the journals of said lower feed rollers. The upper feed rollers 28 are driven by intermeshing spur gears 67 on the respective journals of said upper and lower feed rollers 27 and 28. The discharging 80 rollers 72 and 73, which are adjacent to the hair advancing drum of the last blowing chamber 32, are driven in manner and by means similar to that above described for driving the feed rollers 27 and 28. Said discharging rollers 72 and 73 serve to deliver 85 the cleaned hair out of the discharge end of the machine. The hair advancing drums 26 and 31 are driven by intermeshing spur gears 68 and 69, said spur gears 68 being idler gears driven by the gearing 67, and 90 transmitting motion to the spur gears 69 which are respectively fixed on journals of 95 said hair advancing drums 26 and 31.

When in use, the machine, constructed according to the principles of this invention, 100 functions as follows:—

The hair material to be cleaned is deposited in bulk within the receiving hopper or bin 1. As the hair descends to the bottom of the receiving hopper or bin 1 it engages the rotating feed drum 3, the projecting pins 4 on the surface of which tend to grip the hair so that the same is carried forward and out of the bottom of the receiving hopper or bin for introduction into 105 the interior of the machine. It is highly desirable that a continuously entering uniform quantity of hair be fed into the machine, to the end that the blowing and cleaning functions may be most efficiently attained, without choking or overloading the machine. To this end an automatic feed control, cooperative with the feed drum 3, is provided to automatically regulate and control the quantity of hair delivered into 110 the machine by said feed drum. This automatic feed control comprises the reciprocating scraper plate 5, which is caused to move back and forth over the forwardly rotating surface of the feed drum 3. Said 115 scraper plate 5 is set or adjusted in a desired spaced relation to the surface of the feed drum, so that only a mat or layer of hair of predetermined thickness, and therefore of predetermined quantity, can be car- 120 125 130

ried forward by said feed roller 3 and thus entered within the machine. The reciprocating movement of the scraper plate 5 first withdraws the same from above the surface 5 of the feed drum 3 so that the hair within the hopper or bin 1 may drop upon and be engaged by the pin surface of the feed drum, whereupon a forward movement or 10 thrust of the scraper plate 5 causes the same to pass over the surface of the feed drum to prevent further deposit of hair upon the latter, while at the same time the projecting take-off pins 6 of the free edge of the scraper plate 5 will comb or take off any 15 hair in excess of the thickness of mat or quantity thereof desired to be entered in the machine. By setting the scraper plate closer to or further away from the surface of the feed drum 3, the quantity of admitted hair 20 may be decreased or increased as may be advisable. This automatic feed regulation means of the machine is one of the important novel features of the present invention.

After the hair passes out of the hopper 25 or bin 1 it is carried forward by the feed drum 3 toward the rotating comb plate 16, the pins 17 of which, by intermeshing with the pins 4 of the feed drum, serve by their movement to disengage the hair from the 30 latter, whereupon said hair drops down upon the transfer roller 18. The transfer roller 18 by its movement conveys the hair to the receiving side of the feeding-in rollers 19 and 20, which feed the hair forwardly 35 into engagement with and subject to the teasing, loosening and separating action of the rapidly rotated picking roller 22, whereby the hair fibers are substantially loosened and separated one from another. The rapid 40 rotation of the picking roller 22 produces an ascending air current at the far side of the same, which tends to rise upwardly through the channel or well 25 and thence into the initial blowing chamber 32. The 45 lighter hair fibers tend to follow and ride upon said ascending air current, and are consequently tossed upwardly within the initial blowing chamber and by the process are further loosened and separated, so as to 50 permit dust, dirt and undesirable relatively heavy admixtures to separate and drop away therefrom. Owing to the centrifugal action involved in the movement of the hair material by the picking roller 22, the comparatively heavy admixtures of sand, pieces 55 of hide, small shot, and coarse undesired hair fibers and tufts, tend to be thrown downwardly toward the bottom of the channel or well 25, to pass thence through the bottom 60 opening or slot provided by the partially opened door 24 at the bottom of said channel or well, thus almost immediately effecting a thorough separation of undesired admixtures contained in and among the 65 relatively light or fine hair fibers it is de-

sired to conserve, loosen and clean. The light hair fibers without substantial loss or waste are tossed into the initial blowing chamber 32 by the ascending air current as aforesaid so as to rise upwardly therein 70 until the diminishing force of said ascending air current permits gravity to act upon the hair fibers, which thereupon tend to descend within the far side of the initial blowing chamber 32 so as to be received by 75 or upon the slowly forwardly rotating hair advancing drum 26, and thereby conveyed to the receiving side of the feed-rollers 27 and 28.

The feed rollers 27 and 28 convey the hair 80 fibers forwardly into engagement with and subject to the further teasing and separating action of another rapidly rotated picking roller 30 disposed in the lower open end of a succeeding blowing chamber 32. The rapid 85 rotation of the picking roller 30 also produces an air current which moves both toward the adjacent perforate hair transfer drum 31 (which is spaced forwardly from and opposite to said picking roller 30) and 90 upwardly into said succeeding blowing chamber 32. The centrifugal force produced by the rapidly rotated picking roller 30 tends to cast downwardly into the bottom or under space of the machine remaining 95 undesirable admixtures and coarse hair fibers and tufts, so that the separated lighter or fine hair fibers which it is desired to conserve and clean are further relieved from such undesirable admixtures, and are again 100 tossed upwardly into the succeeding blowing chamber 32 to be further loosened and separated. Owing to the fact that the hair advancing drum is formed by a perforate hollow body, that portion of the air stream, 105 produced by the picking roller 30, which flows toward said hair advancing drum may pass transversely thereinto, and is not dissipated downwardly into the under space of the machine, and thus permitted to carry 110 with it, and consequently to waste, lighter hair fibers which it is desired to conserve. The air thus passing transversely into the interior of the hair advancing drum may 115 pass downwardly and out of the same, but upon emerging impinges upon the underlying deflector plate 33, whereby the same is deflected back toward the picking roller 30 as a counter current of air. The centrifugal 120 force exerted upon the hair material by the picking roller 30 is such, that the heavier or undesired coarse hair fibers or tufts tend to more quickly fly out of the influence of the air stream than do the lighter hair fibers, which tend to more readily follow the movement of the air stream. As a consequence 125 of these tendencies, the counter air current will engage the coarse hair fibers, which tend to fly out of the main forwardly and upwardly flowing air stream, and will re- 130

tard their movement in the latter, thereby assisting the same to more readily and quickly separate themselves from the desired lighter hair fibers and thereupon deposit 5 themselves in the underspace of the machine.

The above described hair blowing and cleaning operations may be successively repeated by employing a series of succeeding 10 blowing chambers 32 equipped with picking rollers 30, hair advancing drums 31 and feed rollers 27 and 28, as shown, until the thoroughly loosened and cleaned hair is finally discharged from the machine by the discharging rollers 72 and 73.

15 By properly adjusting the deflector plates 33, the force of the counter currents of air produced thereby may be more or less strongly opposed to the main forwardly and upwardly moving air streams which are directed into the blowing chambers 32, according to the degree or extent it is desired or necessary to remove relatively coarse hair fibers, etc., from the hair material. The more closely the deflector plates are set toward the hair advancing drums, the more will the counter currents of air be directed so as to join the upward movement of the main air streams into the blowing chambers above, and consequently the less will be the 25 separating effect upon the hair material traveling in said main air streams; while the further (within reasonable limits) the deflector plates are spaced from the hair advancing drums, the more strongly will the counter currents of air be opposed to the main air streams, and consequently the greater will be the separating effect upon the hair material traveling in the latter. This being so it is usually advisable, when a series 30 or plurality of successive blowing chambers 32 are provided, to successively diminish the space between the respective succeeding deflector plates and the hair advancing drums to which they are opposed toward the discharge end of the machine, in the manner indicated in Figure 1 of the drawings.

It will be readily apparent that the machine is provided with closed blowing chambers and a closed underspace, and that consequently the dust, incident to the cleaning 50 of the hair material, will be retained entirely within the machine, therefore the machine, in operation, does not diminish the sanitary condition desired in the work room 55 wherein it may be located.

Having thus described the construction and operation of my invention, I claim:—

1. A blowing machine for the preparation 60 of hair felt, comprising a series of closed blowing chambers, means for transferring hair material under treatment from one blowing chamber to another and finally out of the machine, a rotated picking roller for each blowing chamber adapted to both separate the hair material and produce an as-

cending air current for tossing the separated hair material in each blowing chamber, means for delivering hair material into the receiving end of the machine, and means for removing excess material from the delivering means to automatically control and determine the quantity of material to be treated. 70

2. A blowing machine for the preparation 75 of hair felt, comprising a series of closed blowing chambers, means for transferring hair material under treatment from one blowing chamber to another and finally out of the machine, a rotated picking roller for each blowing chamber adapted to both separate the hair material and produce an ascending air current for tossing the separated hair material in each blowing chamber, and means for delivering into the receiving end of the machine an automatically 80 controlled and determined quantity of the hair material to be treated, comprising a receiving hopper, a rotatable feed drum at the bottom of said hopper, and automatic means for removing from said feed drum hair material in excess of the quantity desired to be delivered into the machine. 85

3. A blowing machine for the preparation 90 of hair felt, comprising a series of closed blowing chambers, means for transferring hair material under treatment from one blowing chamber to another and finally out of the machine, a rotated picking roller for each blowing chamber adapted to both separate the hair material and produce an ascending air current for tossing the separated hair material in each blowing chamber, and means for delivering into the receiving end of the machine an automatically 95 controlled and determined quantity of the hair material to be treated, comprising a receiving hopper, a rotatable feed drum at the bottom of said hopper, a scraper plate mounted to reciprocate intermediate said feed drum and said hopper interior in desired spaced relation to the former, the free edge of said scraper plate having a plurality of projecting take-off pins, and a rotatable comb-plate having comb-pins at its free edges to remove the hair material 100 from said feed drum for transfer to the initial blowing chamber. 110

4. In a hair blowing and cleaning machine, a hopper at the receiving end of said machine, a rotatable feed drum having hair gripping pins on its circumferential surface, the surface of said feed drum forming the bottom of said hopper, and automatic means for removing from said feed drum hair material in excess of the quantity desired to be delivered into the machine for treatment. 120

5. In a hair blowing and cleaning machine, a hopper at the receiving end of said machine, a rotatable feed drum having hair 125

gripping pins on its circumferential surface, the surface of said feed drum forming the bottom of said hopper, a scraper plate concentrically spaced from the surface of said feed drum intermediate the latter and the interior of said hopper, means for reciprocating said scraper plate, the free edge of said scraper plate having a plurality of projecting take-off pins, and a rotatable comb-plate having comb-pins at its free edges to remove the hair material from the gripping pins of said feed drum for deposit within the machine.

6. A blowing machine for the preparation of hair felt, comprising a series of closed blowing chambers, a rotated picking roller for each blowing chamber adapted to both separate the hair material and produce an ascending air current for tossing the separated hair material in each blowing chamber, means to feed the hair material subject to the action of said picking rollers, hollow perforate hair advancing drums to receive and advance the hair material tossed in said blowing chambers, said hair advancing drums being pervious to the air currents produced by said picking rollers, and deflector plates beneath said hair advancing drums for deflecting the air passing through the latter to thereby produce counter air streams directed toward said picking rollers for the purposes described.

7. A blowing machine for the preparation of hair felt, comprising a series of closed blowing chambers, a rotated picking roller for each blowing chamber adapted to both separate the hair material and produce an ascending air current for tossing the separated hair material in each blowing chamber, means to feed the hair material subject to the action of said picking rollers, hollow perforate hair advancing drums to receive and advance the hair material tossed in said blowing chambers, said hair advancing drums being pervious to the air currents produced by said picking rollers, deflector plates beneath said hair advancing drums for deflecting the air passing through the latter to thereby produce counter air streams directed toward said picking rollers for the purposes described, and means for adjusting said deflector plates relative to said hair advancing drums.

8. A blowing machine for the preparation of hair felt, comprising a series of closed blowing chambers, a rotated picking roller for each blowing chamber adapted to both separate the hair material and produce an ascending air current for tossing the separated hair material in each blowing chamber, means to feed the hair material subject to the action of said picking rollers, hollow perforate hair advancing drums to receive and advance the hair material tossed in said blowing chambers, said hair ad-

vancing drum being pervious to the air currents produced by said picking rollers, deflector plates pivoted for movement toward and away from the underside of said hair advancing drums, said deflector plates serving to deflect the air passing through the latter to thereby produce counter air streams directed toward said picking rollers for the purposes described, and an adjustable support for said deflector plates movable to respectively dispose the latter in desired adjusted relation to the respective hair advancing drums with which they cooperate.

9. In a hair blowing and cleaning machine having a closed blowing chamber, a rotated picking roller in the lower portion of said blowing chamber adapted to both separate the hair material and produce an ascending air current for tossing the separated hair material in the blowing chamber, a hollow perforate hair advancing drum adjacent to said picking roller and pervious to the air currents produced by the latter, and a deflector plate beneath said hair advancing drum for deflecting the air passing through the latter to thereby produce a counter air stream directed toward said picking roller.

10. In a hair blowing and cleaning machine having a closed blowing chamber, a rotated picking roller in the lower portion of said blowing chamber adapted to both separate the hair material and produce an ascending air current for tossing the separated hair material in the blowing chamber, a hollow perforate hair advancing drum adjacent to said picking roller and pervious to the air currents produced by the latter, a deflector plate beneath said hair advancing drum for deflecting the air passing through the latter to thereby produce a counter air stream directed toward said picking roller, and means for adjusting said deflector plate relative to said hair advancing drum.

11. In a blowing machine for the preparation of hair felt provided with a series of closed blowing chambers, a hopper at the receiving end of the machine, a rotatable feed drum having hair gripping pins on its circumference, said feed drum forming the bottom of said hopper, a scraper plate having take-off pins concentrically spaced from the surface of said feed drum intermediate the latter and the interior of said hopper, means for reciprocating said scraper plate, a rotatable comb-plate to remove the hair material fed from said hopper by said feed drum, the initial blowing chamber of said series of blowing chambers having an ascending passage or well leading thereto, a picking roll at the lower end of said well, means for feeding the hair material removed from said feed drum subject to the action of said picking roller, each blowing chamber succeeding said initial blowing

- chamber having a rotated picking roller in its lower portion, means for feeding hair material subject to the action of said latter picking rollers, and each blowing chamber 5 having a rotatable perforate hair advancing drum for delivering hair material from one blowing chamber to the picking roller and its feeding means of a succeeding blowing chamber and finally out of the machine.
- 10 12. In a blowing machine for the preparation of hair felt provided with a series of closed blowing chambers, a hopper at the receiving end of the machine, a rotatable feed drum having hair gripping pins on 15 its circumference, said feed drum forming the bottom of said hopper, a scraper plate having take-off pins concentrically spaced from the surface of said feed drum intermediate the latter and the interior of said 20 hopper, means for reciprocating said scraper plate, a rotatable comb-plate to remove the hair material fed from said hopper by said feed drum, the initial blowing chamber of said series of blowing chambers having an 25 ascending passage or well leading therewith, a picking roll at the lower end of said well, means for feeding the hair material removed from said feed drum subject to the action of said picking roller, each blowing chamber 30 succeeding said initial blowing chamber having a rotated picking roller in its lower portion, means for feeding hair material subject to the action of said latter picking rollers, each blowing chamber having a 35 rotatable perforate hair advancing drum for delivering hair material from one blowing chamber to the picking roller and its feeding means of a succeeding blowing chamber and finally out of the machine, said hair 40 advancing drums of the blowing chambers having an ascending passage or well leading therewith, a picking roll at the lower end of said well, means for reciprocating said scraper plate, a rotatable comb-plate to remove the hair 45 material fed from said hopper by said feed drum, the initial blowing chamber of said series of blowing chambers having an 50 ascending passage or well leading therewith, a picking roll at the lower end of said well, means for feeding the hair material removed from said feed drum subject to the action of said picking roller, each blowing chamber 55 succeeding said initial blowing chamber having a rotated picking roller in its lower portion, means for feeding hair material subject to the action of said latter picking rollers, each blowing chamber having a 60 rotatable perforate hair advancing drum for delivering hair material from one blowing chamber to the picking roller and its feeding means of a succeeding blowing chamber and finally out of the machine, said hair 65 advancing drums of the blowing chambers having an ascending passage or well leading therewith, a picking roll at the lower end of said well, means for reciprocating said scraper plate, a rotatable comb-plate to remove the hair material fed from said hopper by said feed drum, the initial blowing chamber of said series of blowing chambers having an 70 ascending passage or well leading therewith, a picking roll at the lower end of said well, means for feeding the hair material removed from said feed drum subject to the action of said picking roller, each blowing chamber having a 75 rotatable perforate hair advancing drum for delivering hair material from one blowing chamber to the picking roller and its feeding means of a succeeding blowing chamber and finally out of the machine, said hair advancing drums of the blowing chambers succeeding said initial blowing chamber being previous to the air currents produced by said picking roller thereof, deflector plates beneath said latter hair advancing drums for deflecting the air passing therethrough to thereby produce air streams counter to the air currents produced by said adjacent picking rollers for the purposes described, and means for adjusting said deflector plates relative to said hair advancing drums. 80
14. In a blowing machine for the preparation of hair felt provided with a series of closed blowing chambers, a hopper at the receiving end of the machine, a rotatable feed drum having hair gripping pins on its 85 circumference, said feed drum forming the bottom of said hopper, a scraper plate having take-off pins concentrically spaced from the surface of said feed drum intermediate the latter and the interior of said hopper, means for reciprocating said scraper plate, a rotatable comb-plate to remove the hair 90 material fed from said hopper by said feed drum, the initial blowing chamber of said series of blowing chambers having an 95 ascending passage or well leading therewith, a picking roll at the lower end of said well, means for feeding the hair material removed from said feed drum subject to the action of said picking roller, each blowing chamber 100 succeeding said initial blowing chamber having a rotated picking roller in its lower portion, means for feeding hair material subject to the action of said latter picking rollers, each blowing chamber having a 105 rotatable perforate hair advancing drum for delivering hair material from one blowing chamber to the picking roller and its feeding means of a succeeding blowing chamber and finally out of the machine, said hair 110 advancing drums of the blowing chambers having an ascending passage or well leading therewith, a picking roll at the lower end of said well, means for reciprocating said scraper plate, a rotatable comb-plate to remove the hair material fed from said hopper by said feed drum, the initial blowing chamber of said series of blowing chambers having an 115 ascending passage or well leading therewith, a picking roll at the lower end of said well, means for feeding the hair material removed from said feed drum subject to the action of said picking roller, each blowing chamber 120 succeeding said initial blowing chamber having a rotated picking roller in its lower portion, means for feeding hair material subject to the action of said latter picking rollers, each blowing chamber having a 125 rotatable perforate hair advancing drum for delivering hair material from one blowing chamber to the picking roller and its feeding means of a succeeding blowing chamber and finally out of the machine, said hair advancing drums of the blowing chambers succeeding said initial blowing chamber being previous to the air currents produced by said picking roller thereof, deflector plates beneath said latter hair advancing drums for deflecting the air passing therethrough to thereby produce air streams counter to the air currents produced by said adjacent picking rollers for the purposes described, deflector plates pivoted for movement toward 130
13. In a blowing machine for the preparation of hair felt provided with a series of closed blowing chambers, a hopper at the receiving end of the machine, a rotatable feed drum having hair gripping pins on its circumference, said feed drum forming the bottom of said hopper, a scraper plate having take-off pins concentrically spaced from the surface of said feed drum intermediate the latter and the interior of said hopper, means for reciprocating said scraper plate, a rotatable comb-plate to remove the hair material fed from said hopper by said feed drum, the initial blowing chamber of said series of blowing chambers having an ascending passage or well leading therewith,

and away from the underside of said hair advancing drums, said deflector plates serving to deflect the air passing through the latter to thereby produce counter air streams directed toward said picking rollers for the purposes described, and an adjustable support for said deflector plates movable to respectively dispose the latter in desired adjusted relation to the respective hair advancing drums with which they co-operate.

15. In a blowing machine, the combination of blower chambers, sieve rollers provided in the under part of said blower chambers, guiding plates associated with the sieve rollers, and a frame for adjustably supporting the guiding plates relative to the sieve rollers for regulating the degree of separation of the hair material.

16. In a blowing machine for the manufacture of hair felt, the combination of a closed feeding device, a plurality of blower chambers, sieve rollers in the under part of said blower chambers, pivoted guiding plates associated with said sieve rollers, and a frame for adjustably supporting said guiding plates with respect to said sieve rollers.

17. In a blowing machine for the manufacture of hair felt, the combination of a closed feeding device, a plurality of blower chambers, sieve rollers in the under part of said blower chambers, pivoted guiding plates associated with said sieve rollers, a frame for adjustably supporting said guiding plates with respect to said sieve rollers,

and means for adjusting the supporting frame for varying the degree of adjustment of the several guiding plates.

18. In a blowing machine for the manufacture of hair felt, the combination of a closed feeding hopper, a pin drum in the lower portion of said hopper, a scraper cooperating with said pin drum, a scraper plate also cooperating with said pin roller, a guiding roller below said scraping ledge for directing the hair to a pair of feeding-in rollers, and a picker roller for removing the hair from said feeding-in rollers, whereby to effect the preliminary separation of the hair material and cast the separated hair material into the first of its blower chambers.

19. In a blowing machine for the manufacture of hair felt, the combination of a closed feeding hopper, a pin drum in the lower portion of said hopper, a scraper cooperating with said pin drum, a scraper plate also cooperating with said pin roller, a guiding roller below said scraping ledge for directing the hair to a pair of feeding-in rollers, a picker roller for removing the hair from said feeding-in rollers, whereby to effect the preliminary separation of the hair material and cast the separated hair material into the first of its blower chambers, and a door in proximity to said picker roller to regulate the air draft through the machine.

In testimony whereof I affix my signature.
WILLY NOACK.
